SPRAY GUN

John A. Wilkins and David Wilkins, Jr.,
New York, N. Y.

Application June 20, 1945, Serial No. 600,628

3 Claims. (Cl. 299—140.1)

(Granted under the act of March 3, 1883, as
amended April 30, 1928; 370 O. G. 757)

1

This invention relates to the art of spray guns, and it comprises a spray gun particularly useful for spraying heavy, thick compositions, and relatively large quantities thereof. Ships' bottoms, for example, are commonly coated with thick, pasty compositions which cannot be handled by conventional spray guns, or can be handled only with great difficulty and at an extremely slow rate.

An object of this invention is to provide a spray gun that will atomize and spray heavy, thick, and pasty compositions.

Another object is to provide a spray gun that will atomize and spray at a high volumetric rate.

Still another object is to provide a spray gun that will effectively coat surfaces at a relatively great distance from the nozzle end of the spray gun.

Further objects and advantages of this invention, as well as its construction, arrangement and operation, will be apparent from the following descriptions and claims in connection with the accompanying drawing, in which,

Fig. 1 is an elevation of a spray gun embodying the present invention.

Fig. 2 is an elevation of the spray gun of Fig. 1, viewed from the left of Fig. 1.

Fig. 3 is an end view of the spray gun of Fig. 2, and looking toward the nozzle orifices.

Fig. 4 is a detailed cross-sectional elevation taken along the line 4—4 of Fig. 2.

Fig. 5 is a perspective view of a portion of the pressure-fluid and composition tubes together with their control valves.

The tube 14 comprises a duct for the passage of coating composition such as paint or other suitable material to be sprayed by means of the device of the present invention, and it is preferably made of brass or similar corrosion-resistant material. Valve 12 is the means by which the flow of coating composition through tube 14 is controlled. The pressure fluid duct is also preferably made of brass or similar corrosion-resistant material and it comprises a single duct including a valve 15, beyond which it is bifurcated to form the tubes 13 parallel to the composition tube 14 and disposed adjacent thereto on opposite sides thereof, the axes of the air tubes 13 and the composition tube 14 being preferably coplanar. The valve 15 regulates and controls the flow of air through the tubes 13.

A concentric bushing 16 having a concentric cylindrical bore is fixed in the end of composition tube 14 to comprise a nozzle therefor, the bore in the bushing 16 providing a cylindrical orifice of

2

predetermined diameter to predetermine the flow-rate of the stream of coating composition emerging therefrom. A flexible hose 17 conducts coating composition under pressure from a conventional pressurized reservoir (not shown) to the composition tube 14, and pressurized air is conducted from any conventional source through a flexible hose 18 to the duct that includes valve 15, thence to the tubes 13.

The tubes 13 are deflected or bent towards each other near their ends to form nozzles 22, which are thus directed to intersect each other and the axis of nozzle 16 at a point beyond and closely adjacent the composition nozzle. Each nozzle 22 is directed at an angle less than 45° with reference to the axis of nozzle 16 so that there is an acute angle between the nozzles 22. An angle of about 30° is preferred between the composition nozzle 16 and each pressure-fluid nozzle 22, and an angle of about 60° between the nozzles 22. See Figs. 1 and 4.

The nozzle 16 of composition tube 11 and nozzles 22 of air tubes 13 are held in fixed relationship by a welded or brazed joint 19, and the ducts 25 upon which valves 12 and 15 are mounted are suitably spaced and rigidly held by a block 20 located adjacent the upper ends of the ducts as viewed in Fig. 2, and inserted between them and suitably fastened as by welding or brazing. It will be apparent that suitable clips or equivalent devices may be utilized to join the component parts of the subject invention and hold them in the desired relationship.

The nozzles 22 are formed by flattening each air tube 13 at its nozzle end, and the orifice of each nozzle 22 is therefore oblong and approximately rectangular. By approximately rectangular, it is meant that the openings are elongated and have substantially parallel sides. The ends of the openings may be square, rounded, or otherwise shaped as desired. The long dimensions of the openings of nozzles 22 are normal to the common plane of the axes of air tubes 13 and composition tube 14 in the embodiment of the disclosure. The flat walls of the nozzles 22 may be parallel for a suitable distance from the nozzle openings or may converge slightly toward the nozzle openings. The bends in the air tubes 13 where the nozzles 22 begin are preferably smooth and of large radius. The shape of nozzles 22, it will be apparent, is such as to form flat streams of air, directed toward each other so as to converge at an acute angle.

The inside surface of bushing 16 is smooth and well tapered so as to offer as little resistance as

possible to the flow of coating composition therethrough. The exit opening of bushing 16 is preferably, but not necessarily, round. The inside diameter of the nozzle end of bushing 16, it will be noted, is considerably smaller than long dimension of each oblong orifice 22, the longer dimension of which therefore extends beyond the span of the orifice of the composition nozzle bushing 16.

In the operation of the portable spray gun of the present invention, valve 15 is opened and pressurized air is permitted to flow through air tubes 13 and out the elongated openings of their nozzles 22. Air tubes 13 should be straight for a sufficient length back from their nozzles 22 to insure that air at the nozzle ends will not be moving in turbulent flow. Upon valve 12 being opened, a stream of coating composition will be forced into the impinging flat streams in their area of impingement, and will be broken into an extremely fine spray and impelled outward.

Using a coating composition of moderately heavy consistency, an air pressure of 100 pounds per square inch, and the same pressure behind the coating composition in composition tube 11, one obtains an excellent spray which will travel several feet without excessive divergence. The long carry of this spray enables an operator to cover a large area with a minimum of movement, and reduces the complexity and size of the scaffolding required for many jobs. Lesser and greater pressures may be used, as available and as desired. Optimum pressures will vary with the consistency of the coating composition being applied, the thickness of coat desired, air temperature and other factors.

The oblong openings of nozzles 22 must be wide enough so that the flow of air through them is not unduly restricted, and yet narrow enough so that the stream of air issuing therefrom has a definite flat form, a width of from 10 to 50% of the length of the openings being suitable. The longer dimension of the orifice of each tube 13 extends further from its nozzle axis in both directions than the orifice of bushing 16 extends from its axis. The length of the air openings must be sufficiently greater than the diameter of the opening in bushing 16 to insure that the entire stream of coating composition emerging from composition tube 11 is caught in the area of impingement of the air streams. As long as the relative proportions of the oblong air openings are maintained, the diameter of the nozzle opening of bushing 16 may be made as large as necessary to attain any desired rate of flow of the coating composition.

It is to be understood that various modifications and changes may be made in this invention without departing from the spirit and scope thereof as set forth in the appended claims.

The invention described herein may be manufactured and used by or for the Government of

the United States of America for governmental purposes without the payment of any royalties thereon or therefor.

What is claimed is:

- 5 1. In a portable spray gun, a tube for the composition to be sprayed comprising a nozzle at its end, the nozzle comprising a cylindrical orifice; a plurality of tubes for pressure fluid, each pressure-fluid tube being flattened at its end to form a nozzle comprising an oblong orifice, the pressure-fluid and composition tubes being rigidly secured in positions adjacent each other at their nozzle end portions to locate the several pressure-fluid nozzles symmetrically on respectively opposite sides of the composition nozzle, the longer dimension of each oblong pressure-fluid orifice extending transversely of a line through the centers of the nozzle orifices of the several pressure-fluid and composition nozzles and beyond the span of the composition nozzle, each of the pressure-fluid tubes being bent near its nozzle end to direct its nozzle toward the axis of the composition nozzle to intersect the composition nozzle axis at a point beyond and closely adjacent the composition nozzle, whereby the composition flowing from the composition nozzle is broken into a spray and impelled outwardly and away from said nozzles.
- 10 2. In a spray gun as defined in claim 1, the composition nozzle comprising a bushing having a concentric cylindrical bore, and the bushing being secured in the end of the composition tube.
- 15 3. In a spray gun as defined in claim 1, the axis of each pressure-fluid nozzle being directed to intersect the axis of the composition nozzle at an angle of approximately 30 degrees.
- 20 35
